Primary Examiner — David G Muller*Assistant Examiner* — Nathan M Johnston(74) *Attorney, Agent, or Firm* — Tommy SF Wang; Wang IP Law Group, P.C.**CLAIM**

The ornamental design for a hanging shelf, as shown and described.

DESCRIPTION

FIG. 1 is a perspective view of a hanging shelf showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of an indicated portion of FIG. 1.

The broken line portions of the hanging shelf in FIGS. 1-7 represent unclaimed portions of the claimed design and form no part thereof.

1 Claim, 8 Drawing Sheets(56)
